UNITED STATES PATENT OFFICE.

FRANZ LEHMANN, OF BERLIN, GERMANY.

DRIVING-GEAR FOR SEWING-MACHINES.

SPECIFICATION forming part of Letters Patent No. 256,842, dated April 25, 1882.

Application filed September 15, 1881. (No model.) Patented in Germany November 19, 1880.

To all whom it may concern:

Be it known that I, FRANZ LEHMANN, of Berlin, in the Empire of Germany, have invented certain new and useful Improvements 5 in Driving-Gear for Sewing-Machines, of which the following is a specification.

In the use of sewing-machines operated by foot-power it becomes often desirable to drive the same during more or less long periods by 10 hand to produce certain classes of work. For this purpose a handle is generally attached to the fly-wheel of the machine—that is to say, to the heavy driving-pulley on the main shaft of the sewing-machine proper—the belt or cord 15 from the large pulley on the crank-shaft being disconnected when it is desired to drive the machine by hand. This arrangement has the disadvantage that the motion of the machine when driven by hand is much slower than is in 20 most cases desirable. I have devised an arrangement of parts whereby hand or foot power may be applied without reducing in either case the speed of the machine. The invention may be carried out either in the shape of an attachment 25 to existing machines, or the device may form part of the general construction in the building of new machines. I will describe it as applied to what is known as a "Singer Shuttle-Machine," and have so represented it in the 30 accompanying drawings, in which—

Figure 1 is a side elevation of the rear part of a sewing-machine provided with my device, certain parts being shown in section. Fig. 1^a shows in side elevation, in section, and in end 35 elevation certain parts on a larger scale than Fig. 1. Fig. 2 is an end elevation of the parts shown in Fig. 1. Fig. 3 is a plan thereof partly in section; and Fig. 3^a shows in section and in elevation, on a larger scale, certain parts 40 in a position corresponding to Fig. 3. These drawings form a part of this specification and represent what I consider the best means of carrying out the invention.

Similar letters of reference indicate corresponding parts in all the figures.

The fly-wheel A, constituting also pulley, turns loosely upon a bushing, a, which is firmly attached to a standard, B, mounted in any suitable manner to the fixed frame of the sewing-machine. The driving-shaft b passes

through the bushing a, and is supported therein, as shown. A peculiarly-shaped pin, c, is screwed into the end of shaft b, so as to overhang the bushing or bearing a. This pin c supports a clutching head or button, C. The 55 pin c is formed with a round part, c', and a flattened part, c², the width of the latter being greater than the diameter of part c'. The inner part of button C, which faces the fly-wheel A, is formed with a central hole of the same diameter as part c', so as to admit of both a sliding and turning motion of the button C thereon, and in this hole are formed two feather-grooves of sufficient size to accommodate the flattened part c² of pin c. The rear or other part of button C has a chamber in which plays a spiral spring encircling the part c', and which abuts on one side against the shoulder of the chamber in the button C, and on the other side against a head fixed upon the pin c, as shown, 60 and thus tends to force the button C constantly toward the fly-wheel B. The inner face of the button C is formed with two clutch-claws, d d', capable of engaging with two corresponding claws, d² d³, on the face of the fly-wheel. 65

k is a ring of internal teeth, which may either be formed in one with the fly-wheel or be fixed thereto in any suitable reliable manner.

f is a shaft supported in a bearing fixed upon the neck of the machine, and in another bearing formed on the standard B. This shaft is capable of a turning and an endwise motion in its bearings, and carries two gear-wheels, g and h, the first of which, g, engages with a wheel, i, fixed upon the main shaft b, while the 85 other, h, engages in the ring of teeth k when the shaft is moved toward the right in Fig. 1, while in the position shown in the figure both wheels g and h are not affected by or do not affect the corresponding wheels, i and k. In 90 either of these two positions the shaft f may be reliably held by turning the lever l so as to engage the same in either of the grooves m or m' turned into the shaft f.

D is the ordinary spooling attachment of a 95 Singer machine.

When the parts are in the position shown in Figs. 1, 1^a, and 2—that is to say, with the clutch C engaged and with the gear-wheels g and h disengaged—the machine is ready to be 100

operated by foot-power, the pulley A transmitting the motion to the clutch-button C, from which it is in turn transmitted through the flattened part c^2 of the pin c to the main shaft b.

5 When it is desired to drive the machine by hand with about the same velocity as by foot-power the belt is taken off the pulley A, the clutch-head C is drawn backward and turned quarter round, so that when released it abuts 10 against the shoulders of the flattened part c^2 of pin c, thus holding its claws d d' out of engagement from the claws d d' of the pulley B; then the shaft f is liberated by turning the lever l and moved toward the right, thus engaging wheel h with k and wheel g with i. On locking the shaft f in this new position by means of lever l, as above described, hand-power may be applied to the pulley B by means of the crank handle, whereby the shaft 15 b may be driven at about the same speed as before, the motion being transmitted from the pulley A through k, h, f, g, and i.

When it is desired to drive the machine slowly by hand the clutch C is kept engaged 20 with the pulley A, and the wheels g h are maintained out of engagement with their respective wheels i and k, the same as for operating by foot-power, the belt being of course taken off. For spooling both the clutch C and the wheels 25 g and h are disengaged, whereupon the spooling may be effected by foot or hand power without setting any part of the sewing mechanism in motion.

Modifications may be made in the details 30 without departing from the general principles of the invention. The pin c, instead of having a flattened part, c^2 , may have a feather extending a corresponding part of its length, the proportions of the wheels g h i k may be varied to 35 a considerable extent, or more wheels, g i, of different proportions, may be used, so as to obtain various speeds, according to which set is engaged, care being taken to make the ring of teeth k sufficiently wide to maintain the wheel 40 h engaged therewith as long as any of the sets g i are engaged. The teeth k may be internal or external. The arm n, connecting the second

bearing of the shaft f with the standard B, may be omitted. I prefer, however, the construction shown as affording great rigidity of the fixed 50 parts.

I claim as my invention—

1. In a sewing-machine, the fly-wheel A, mounted concentrically with the main shaft b on a bushing, a, fixed to a rigid part of the frame, in combination with said main shaft and said bushing, and with a clutch, C, carried on an extension of the main shaft and capable of being engaged with and disengaged from the pulley A, substantially as herein specified. 60

2. As a sewing-machine, the fly-wheel A, mounted concentrically with the main shaft b, but capable of turning independently thereof, in combination with said main shaft, with oscillating gearing between the two, means for 65 engaging and disengaging such gearing, and with a clutch, C, substantially as and for the purposes herein specified.

3. As a sewing-machine attachment, the standard B, having a bushing, a, capable of receiving the fly-wheel A, in combination with the clutch C for connecting the fly-wheel and main shaft of the machine, substantially as herein specified. 70

4. As a sewing-machine attachment, the standard B, having the bushing a, and a suitable bearing or bearings for a longitudinally-movable shaft carrying accelerating gearing, in combination with such shaft and gearing, and with a toothed circle, k, revolved by the 80 fly-wheel, the gear-wheel i, and the clutch C, all arranged to serve relatively to each other and to the main shaft b of the machine, substantially as and for the purposes herein specified. 75

In testimony whereof I have hereunto set my hand at Berlin, Prussia, this eleventh day of March, one thousand eight hundred and eighty-one, in the presence of two subscribing witnesses.

FRANZ LEHMANN.
